DESIGN FOR A DRESS

Isidor Kalmis, New York, N. Y.

Application September 27, 1937, Serial No. 71,814

Term of patent 3½ years

To all whom it may concern:

Be it known that I, Isidor Kalmis, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The design is characterized by the combination on the dress disclosed of the specific puffed configurations on the waist and collar portions, as shown.

I claim:

The ornamental design for a dress, substantially as shown, and described.

ISIDOR KALMIS.
